OUTDOOR SWITCH BOX

Filed May 13, 1929

INVENTOR
Henry G. Nichols.

BY
Wesley S. Barr
ATTORNEY

UNITED STATES PATENT OFFICE

HENRY G. NICHOLS, OF MANSFIELD, OHIO, ASSIGNOR TO WESTINGHOUSE ELECTRIC & MANUFACTURING COMPANY, A CORPORATION OF PENNSYLVANIA

OUTDOOR SWITCH BOX

Application filed May 13, 1929. Serial No. 362,698.

My invention relates to switch boxes and particularly to boxes for enclosing switches that are located exteriorly of buildings and are subjected to atmospheric conditions, such as rain, sleet and snow.

An object of my invention is to provide an outdoor box for containing electrical apparatus that is rain-proof and is designed to readily shed water so that it may dry quickly.

Another object of my invention is to provide an out-door box for electrical devices that may be made of a single sheet of metal and be provided with a door particularly designed to shed water and prevent moisture from entering the box.

These and other objects that will be made apparent throughout the further description of my invention are obtained by means of the switch-box apparatus hereinafter described and illustrated in the accompanying drawing wherein

Figure 1 is a front elevational view of a switch box embodying features of my invention;

Fig. 2 is a longitudinal section through the switch box, taken on the line II—II of Fig. 1;

Fig. 3 is a transverse section through the switch box, taken on the line III—III of Fig. 2; and

Fig. 4 is a detail view, in section, of a modified arrangement for holding the cover on the switch box.

Referring to the drawing, the switch box comprises a box structure, five walls of which are formed from a single piece of sheet metal so shaped and bent as to provide a rear wall 4, side walls 5 and 6, a top wall 7 and a bottom wall 8. The side walls are formed in the shape of a parallelogram, with the top and bottom edges sloping downward toward the front edge of the side walls. The top 7 is rectangular in shape and is provided with side flanges 9 which overlap the upper sloping edges of the side wall on the outer sides thereof in such manner that any water falling upon the top wall will be deflected to the outer surfaces of the side walls. The

front edge of the top wall 7 is provided with a depending flange 12.

The bottom wall 8 is provided with side flanges 13 which overlap the side walls 5 and 7 on the inner sides of the side walls, as indicated in Figs. 2 and 3. By reason of this construction, water running down the outer surface of the side walls falls off at the bottom edge and cannot enter the interior of the box, since the flanges 13 are disposed interiorly of the box. The bottom wall 8 is also provided with a portion 14 that extends beyond the front edges of the side walls, as indicated in Figs. 1 and 2, the extended portion being in the same plane as the main portion of the bottom wall.

A sheet-metal door 15 is pivotally supported by hinges 16, the straps of which are riveted to the flange 12 and the upper portion of the door which is supported in such manner that its upper edge lies interiorly of the flange 12 in order to shed water falling upon the top wall 7 and prevent it from entering the interior of the housing. The side edges of the door 15 are provided with flanges 17 that overlap the front edges of the side walls on the outer sides of the side walls and thus prevent rain water blowing against the cover or flanges thereof from entering the interior of the box.

It will be obvious, however, that the hinges 16 may be dispensed with if desired, the cover 15 extending upward inside the flange 12, and being held in place thereby, the latter being slanted downward and outward slightly from the vertical to permit the cover 15 to slip out readily when being removed. Fig. 4 shows this arrangement.

The cover is designed to swing outwardly about a horizontal axis, and the lower edge thereof is provided with an outwardly extending flange 18 that engages the extending portion 14 of the bottom wall, as indicated in Fig. 2, when the cover is in closed position. The flange 18 and the extending portion 14 of the bottom wall are provided with registering openings 19 and 21, respectively, for receiving the wire 22 of a seal 23 for preventing access to the interior of the box by unauthorized persons.

A latch 24 is pivoted to the side wall 6 of the box and is operated by an exteriorly extending shaft 27 and a handle 28 to engage the latch plate 29 on the inner face of the door and serve to latch the door in closed position.

As indicated in Figs. 2 and 3, I have shown a two-pole knife switch mounted in the housing, the switch comprising the insulating base 31 provided with hinge jaws 32 and contact jaws 33. The switch blade 34 is hinged to the jaws 32 and is provided with an insulating handle 35. The jaws 32 and 33 are provided with terminals 36 to which conductors (not shown) may be connected. The top and bottom walls are provided with outwardly extending bosses 37 having surfaces 38 extending in planes normal to that of the rear wall 4 and parallel to each other. These surfaces are provided with knockouts 39 of the usual construction which may be knocked out when desired to provide openings for receiving wiring conduit (not shown). The side walls 5 and 6 are also provided with knockouts 41 which may be removed to provide openings for receiving the conduit at the sides of the housing when desirable.

It will be apparent from the foregoing that a rain-proof housing is provided that may be readily formed of sheet metal and be effective for the purpose intended and relatively inexpensive.

While I have illustrated but one embodiment of my invention, it will be apparent to those skilled in the art that various changes, modifications, substitutions, additions and omissions may be made in the apparatus illustrated without departing from the spirit and scope of my invention as set forth in the appended claims.

I claim as my invention:

1. A box for electrical devices having its top and bottom walls sloping downward toward the front thereof, the top wall being provided with a flange depending from the front edge thereof and a movable cover having its upper edge extending beneath the said flange and hinged thereto and provided with side flanges overlapping the side walls of the box.

2. A box for electrical devices having its top and bottom walls sloping downward toward the front thereof, the top wall being provided with a flange depending from the front edge thereof and the bottom wall having a portion projecting forwardly beyond the front edges of the side walls, and a cover having its upper edges extending beneath the flange on the top wall and provided with side flanges overlapping the side walls of the box and a bottom flange projecting forwardly for engaging the said portion of the bottom wall.

3. A box for electrical devices having its

top and bottom walls sloping downward toward the front thereof, the top wall being provided, at its front edge, with a depending flange, and the bottom wall being provided with a portion extending beyond the side walls of the box and a door for the box hinged thereto and having a portion adjacent the hinge overlapping the said flange in the inside thereof and a flange adjacent to the free edge thereof for engaging the extending portion of the bottom wall.

4. A box for electrical devices having its top and bottom walls sloping downward toward the front thereof, the top wall being provided, at its front edge, with a depending flange, and the bottom wall being provided with a portion extending beyond the side walls of the box and a door for the box hinged thereto and having a portion adjacent the hinge overlapping the said flange on the inside thereof and a flange adjacent to the free edge thereof for engaging the extending portion of the bottom wall and a sealing means on the door flange and the extending portion.

5. A box for electrical devices comprising a box having rear, side, top and bottom walls made from a single sheet of metal bent to bring the side walls into cooperative relation with the top and bottom walls, the top wall being provided with two side flanges overlapping the outside walls on the outer sides thereof and the bottom wall being provided with two side flanges overlapping the side walls on the inner sides thereof, whereby the box is adapted to shed rain without directing water to the interior of the housing.

6. A box for electrical devices comprising a box having rear, side, top and bottom walls made from a single sheet of metal bent to bring the side walls into cooperative relation with the top and bottom walls, the top wall being provided with two side flanges overlapping the outside walls on the outer sides thereof and the bottom walls being provided with two side flanges overlapping the side walls on the inner sides thereof, whereby the box is adapted to shed rain without directing water to the interior of the housing, the front edge of the top being provided with a depending flange, and a door for the box mounted thereon for rotation about a horizontal axis adjacent the depending flange and having a portion overlapping the last said flange on the inside thereof and side flanges overlapping the side walls on the outer side thereof.

7. A box for electrical devices comprising a box having rear, side, top and bottom walls made from a single sheet of metal bent to bring the side walls into cooperative relation with the top and bottom walls, the top wall sloping downward toward the front and being provided with two side flanges overlapping the outside walls on the outer sides thereof and the bottom wall sloping down-

ward toward the front and being provided with two side flanges overlapping the side walls on the inner sides thereof, whereby the box is adapted to shed rain without directing 5 water to the interior of the housing.

8. A rain-proof box for electrical devices comprising a box having side walls in the form of a parallelogram and end walls co-operating therewith and one of said end 10 walls sloping downward toward the front of the box to readily shed water, and having an outwardly extending boss having a surface normal to the plane of the rear wall provided with means for receiving wiring 15 conduit.

9. A box for electrical devices having its top wall sloping downwardly toward the front thereof and provided with a flange depending from the front edge thereof and a 20 movable cover for the front of said box hinged to said flange and having its upper edge extending beneath said flange.

10. A box for electrical devices having its top wall sloping downwardly and provided 25 with a flange depending from the lowermost edge of said top wall and a movable cover hinged to said flange and having its upper edge extending beneath said flange and having 30 side flanges overlapping the side walls of the box.

11. A box for electrical devices having its top wall provided with a depending flange and its bottom wall having a portion projecting forwardly beyond the front edges of the 35 side walls, and a cover having its upper edge extending beneath the flange on the top wall and having a bottom flange projecting forwardly for engaging the projecting portion of the bottom wall.

40 12. A box for electrical devices having its top wall provided with a depending flange and its bottom wall having a portion projecting forwardly beyond the front edges of the side walls, and a cover having its upper 45 edge extending beneath the flange on the top wall and having a bottom flange projecting forwardly for engaging the projecting portion of the bottom wall and having side flanges overlapping the side walls of the box.

50 In testimony whereof, I have hereunto subscribed my name this 6th day of May, 1929.

HENRY G. NICHOLS.
